UNITED STATES PATENT OFFICE.

IRA ORVILLE WRIGHT AND JOHN HANCOCK FARLOW, OF BALTIMORE, MARYLAND, ASSIGNORS TO FARLOW DRAFT GEAR COMPANY, OF BALTIMORE, MARYLAND, A CORPORATION OF DELAWARE.

DRAFT AND BUFFING GEAR FOR CARS.

No. 841,757.

Specification of Letters Patent.

Patented Jan. 22, 1907.

Application filed March 22, 1905. Serial No. 251,526.

To all whom it may concern:

Be it known that we, IRA ORVILLE WRIGHT and JOHN HANCOCK FARLOW, citizens of the United States, residing at Baltimore city, 5 State of Maryland, have invented new and useful Improvements in Draft and Buffing Gear for Cars, of which the following is a specification.

The object of our invention is the provision 10 of certain improvements in draft and buffing gear for cars and of a character somewhat similar to the improvements patented to us on September 22, 1903, No. 739,770.

The present invention consists in certain 15 novelties of construction and combinations and arrangements of parts, as hereinafter set forth and claimed.

The accompanying drawings illustrate an example of the physical embodiment of our 20 invention or improvements constructed according to the best mode we have so far devised for the practical application of the principle.

Figure 1 is a vertical sectional view in elevation of the gear, taken on the longitudinal dotted line of Fig. 2. Fig. 2 is a half top plan and half horizontal sectional view of the gear, the center sills and floor being removed.

Fig. 3 shows a face view of a cheek-plate. Fig. 4 is an edge view of Fig. 3. Figs. 5, 6, 30 and 7 are views of one of the follower-blocks, which are of identical construction, so as to be interchangeable. Fig. 8 is a face view of a link.

Referring to the several figures, the numeral 1 designates one of the two center sills, which are of ordinary construction; 2, the draft sills or timbers located beneath the center sills and secured to the latter by bolts;

3, the body-bolster, in this instance consisting of two metallic plates spaced apart at their centers and united at their ends in a well-known manner; 4, a filling-block located 45 between the draft-timbers and to which it is bolted and bearing against the body-bolster; 5, three elongated slots in the draft-sills; 6, the two cheek-plates, each of which is seated or countersunk within the face of the draft-timber; 7, elongated slots in the cheek-plates, 50 which slots correspond with the slots 5 in the draft-timbers; 8, the coupler and draw-bar; 9, a horizontal hole or passage through the draw-bar shank; 10, the front follower-block;

11, the rear follower-block, identical in construction with the front block, so as to be interchangeable therewith; 12, the horizontal holes through the blocks; 13, the guide-pins; 14, the spring-retaining lugs or pins, each block having two, as shown; 15, two helical springs arranged parallel one above the other and retained in position by engagement with the lugs or pins upon the blocks; 16, the two side links; 17, elongated slots in the links; 18, the draft-keys, with tapered ends; 19, the carry-iron for the draw-bar; 20, the buffer-block; 21, a seat in the filling-block 4 for the reception of a guide-pin of the rear follower-block, and 22 is a seat in the end of the draw-bar for the pin upon the front follower-block.

The relative arrangement of the several parts and elements is clearly shown by the drawings, the keys being passed through the holes or passages in the end of the draw-bar and follower-blocks, and likewise through the elongated slots in the draft-sills, cheek-plates, and links. Cotters may be employed 70 to hold the keys in place when necessary.

As shown, the parts are in their normal positions, the front key being at the middle of the front elongated slots in the draft-timbers 80 and the middle and rear keys being at the extreme ends of the elongated slots. The front key is movable one and three-fourths inches in either direction backward and forward. The middle key can move rearwardly 85 one and three-fourths inches, and the rear key can move forwardly a like distance. The springs are slightly under compression when the gear is assembled.

The *modus operandi* is as follows: In drawing the middle key and front follower-block are stationary, while the draw-bar, front and rear keys, the side links, and rear follower-block move forwardly, and at the same time the springs are compressed. The central elongated slots in the links move over the middle key as the draw-bar advances. When the front and rear keys have moved approximately one and three-fourths inches, they reach the ends of the elongated slots in the draft-timbers and transmit and distribute the strains which have not been absorbed by the springs to the draft-timbers at six points throughout the length of the same.

In buffing the rear key and rear follower-block are stationary, while the draw-bar and

coupler, the front and middle keys, and the front follower-block move rearwardly, at the same time compressing the springs. The side links do not move, as they are provided with elongated slots, in which the front and middle keys travel. When the front and middle keys have moved approximately one and three-fourths inches, they reach the ends of the elongated slots in the draft-timbers and transmit and distribute the shocks and strains not absorbed by the springs through the draft-timbers at six separate points, as is obvious, and also to the filling-block 4, against the end of which the rear follower-block has a frictional bearing.

It is clear from the foregoing description that we have produced a draft and buffing gear which is superior to others of a well-known construction. We dispense with the use of the weak tail-bolt, and especially the riveted yoke, which renders repairs difficult, it being necessary for two or more men to apply or replace gears embracing these elements, as means must be provided for compressing the springs before they can be inserted between the follower-plates. Moreover, in buffing and drawing the strain and shocks are usually concentrated at a single point in each draft-sill.

30 With our construction one man can apply or replace the several parts of the gear, for when a coupler, spring or springs, follower-block, or link is to be removed it is necessary only to drive out a key, make the desired change, and replace the key and drive the same into position, the taper upon the end of the key compressing the spring or springs as the key moves to its normal position within the slots of the draft-timbers.

40 In buffing and drawing our gear transmits and distributes the strains and shocks throughout the length of the draft-timbers and to the filling-block.

The operation by which the initial strains are taken by the spring or springs and the remaining vis viva is distributed through the draft-sills at a plurality of separate points in each is of great importance, as it prevents the liability of tearing the timbers from the floor-sills and the bending or breaking of parts of the gear.

While we have illustrated our improvements applied to a car having separate slotted draft-timbers, we do not intend to restrict ourselves to such application, as the gear may be used with deep metallic center sills having slots, or other slotted supports may be employed at the will of the constructor. Modifications and changes may also be introduced in the shape and arrangement of the movable elements of the gear without constituting substantial departures.

What we claim is—

1. The combination in a draft and buffing gear, of a coupler and draw-bar; a front fol-

lower-block; a rear follower-block; a spring or springs between the blocks; slotted links; and keys, all of which are movable within the slots of the links and the gear; said links taking the strains and being movable relative to one of the keys in drawing.

2. The combination in a draft and buffing gear, of a coupler and draw-bar; a front follower-block with a perforation; a rear follower-block; a spring or springs between the blocks; slotted links which latter take the strains; and keys one of said keys being passed through the front follower-block and movable with said block; the slots in the links being adapted to move over one of the keys in drawing and the links during the act of buffing to remain stationary.

3. The combination in a draft and buffing gear, of a coupler and draw-bar; a front movable follower-block; a rear movable follower-block; a spring or springs between the blocks; links each having two elongated slots, said links taking the strains in drawing; keys; and slotted supports for the keys; the front and middle keys only being adapted to move within slots in the act of buffing, and one of the elongated slots in each link to move over a key during the act of drawing.

4. The combination in a draft and buffing gear, of a draw-bar and coupler; supports having three elongated slots; three keys movable in the slots; two slotted links, the central slots being elongated one side of the key; a front follower-block; a rear follower-block; and a spring or springs between the follower-blocks; said draw-bar being provided with a perforation and within which is located a key, and said links imparting motion to the rear key and taking the strains in drawing.

5. The combination in a draft and buffing gear, of a coupler and draw-bar; a perforated follower-block in the rear of the end of the draw-bar; a rear follower-block; a spring or springs between the blocks; slotted supports or draft-timbers; slotted links; and keys within the perforations of the draw-bar, blocks, links and supports; the front slots in the supports being elongated each side of the front key and the other slots one side of a key, and the links taking the strains in drawing.

6. The combination in a draft and buffing gear, of supports, each having three slots; a draw-bar with a perforation; a front follower-block in contact with the end of the draw-bar and having a perforation; a perforated rear follower-block; a spring or springs between the follower-blocks; two links, each having three slots, the central and front ones elongated; and three keys within the perforations of the several elements; the keys being movable and the rear and middle keys, when the parts are assembled, occupying the rear and front portions of the elongated slots in the supports.

7. The combination in a draft and buffing gear, of slotted supports; perforated follower-blocks located between the supports; a spring or springs between the follower-blocks; two slotted links located between the supports and one on each side of the follower-blocks; keys; and a coupler and draw-bar; the front key being located in the center of the slots in the supports and movable with the draw-bar, and the other keys each being movable in one direction only from normal position. 70

8. The combination in a draft and buffing gear, of slotted supports, all the slots being elongated; a rear follower-block with a perforation; slotted links between the supports, two of said slots being elongated; a spring or springs in front of the follower-block; a movable key passed through the rear slots in the supports, the follower-block, and the rear slots in the links said key being movable from its normal position in a forward direction only; a movable key located within the slots of the supports and the slots of the links in front of the spring or springs; and a draw-bar and coupler; the front ends of the links being secured to the draw-bar, and said links being movable relative to the movable key located in front of the spring or springs, in drawing. 80

9. The combination in a draft and buffing gear, of a draw-bar; links which take the strains in drawing; means including springs for holding the draw-bar in normal position; and three movable keys for arresting the inward and outward travel of the draw-bar when moved from its normal position in either direction the rear key being movable from its normal position in a forward direction only; in substance as set forth. 90

10. The combination in a draft and buffing gear provided with supports having slots, of a coupler and draw-bar; a front follower-block; a rear follower-block; a spring or springs between the blocks; slotted links which take the strains in drawing; and keys; the front and middle keys only being adapted to move rearwardly in buffing, and the front and rear keys only to move forwardly in drawing. 100

11. The combination in a draft and buffing gear having slots, of a coupler and perforated draw-bar; a front follower-block with a hole; a rear follower-block; a spring or springs between the blocks; links; and keys; the front and middle keys and the front follower-block being adapted to move rearwardly during the act of buffing, and the rear key to remain stationary. 110

12. The combination in a draft and buffing gear, of a coupler and draw-bar; a front follower-block; a rear movable follower-block; a spring or springs between the blocks; links which take the strains in drawing, each having elongated slots; keys; and slotted sup- 120

ports for the keys; all said keys being adapted to move within slots, the rear key movable in a forward direction only, and the central elongated slots of the links adapted to move over a key during the act of drawing. 130

13. The combination in a draft and buffing gear, of a draw-bar and coupler; supports each having three elongated slots; three movable keys in the slots; two slotted links which take the strains in drawing, the said slots being elongated so the front and middle keys may move within the slots; a front follower-block; a rear follower-block movable from its normal position in a forward direction only; and a spring or springs between the follower-blocks; said draw-bar being provided with a perforation and within which is located a key. 75

14. The combination in a draft and buffing gear, of a coupler and draw-bar; a front follower-block at the rear of the end of the draw-bar; a rear follower-block; a spring or springs between the blocks; slotted supports or draft-timbers; slotted links; and keys; the central key and front follower-block being movable together, and the slotted links transmitting motion to the rear key when the draw-bar is advanced in drawing. 85

15. The combination in a draft and buffing gear, of a coupler and draw-bar; slotted supports; follower-blocks; springs between the follower-blocks; slotted links; and keys supporting the links, front and rear follower-blocks and springs, the front follower-block and key passing through the same being united so that they will travel together; said links being located between the slotted supports and the follower-blocks and serving to transmit motion from the draw-bar to the rear key in drawing. 95

16. The combination in a draft and buffing gear, of a coupler and draw-bar; slotted supports; follower-blocks; slotted links; keys which support the links; and springs; the front key being movable in two directions and the other keys being each movable in one direction from its normal position. 110

17. The combination with a draft and buffing gear, constructed substantially as set forth, of a draw-bar; springs; follower-blocks; two slotted links; slotted supports; keys, all of which are movable, the front follower-block and the key passed through the same being movable together; and said links being located between the slotted supports and the draw-bar and spring or springs. 115

18. The combination with a draft and buffing gear, constructed substantially as described, of draft timbers and plates, each having three elongated slots for the reception of movable keys; one of said slots being elongated on both sides of a key and the other slots on one side of a key only when the keys are in operative positions. 125

19. The combination in a draft and buff- 130

- ing gear, of slotted supports, all of said slots being elongated; follower-blocks located between the supports; a spring or springs between the follower-blocks; two slotted links located between the supports and one on each side of the follower-blocks; keys; and a coupler and draw-bar; the front follower-block and the key passing through the same being movable together.
20. The combination in a draft and buffing gear, of slotted supports, all the slots being elongated; a rear follower-block with a hole therethrough; slotted links between the supports and one link on each side of the follower-block; a spring or springs in front of the follower-block; a movable key passed through the rear slots in the supports, the follower-block, and the rear slots in the links, said key being movable in one direction only from its normal position; a movable key located within slots of the supports and slots of the links and in front of the spring or springs; and a draw-bar and coupler; the front ends of the links being secured to the draw-bar, and said links being movable relative to the said movable key.
21. The combination in a draft and buffing gear, of supports having slots, a coupler and draw-bar; a front follower-block; a rear follower-block; slotted links; keys supporting the draw-bar and follower-blocks and located within the slots of the supports; and two springs located side by side one above the other in a vertical plane between the follower-blocks; the front key and the middle key only being movable in buffing and the front and rear keys only in drawing.
22. The combination in a draft and buffing gear, constructed substantially as described, of two slotted follower-blocks of identical construction, and provided with lugs 13 and lugs 14 for entering the coils of springs so that they may be interchangeable; a draw-bar and coupler; links; and keys, said keys being located within the slots of the follower-blocks.
23. The combination in a draft and buffing gear, of slotted supports; a draw-bar and coupler; front and rear follower-blocks; slotted links; keys supporting the movable parts of the gear; springs located between the follower-blocks; and a fixed block located between the supports in the rear of the rear follower-block and against which the rear follower-block bears in buffing.
24. The combination in a draft and buffing gear, of a coupler and draw-bar with a slot; supports with elongated slots; keys within the slots and one of said keys passed through the slot in the draw-bar; a rear follower-block having a bearing against the rear key; a front follower-block bearing against the end of the draw-bar; means for limiting the forward movement of the front follower-block; a spring or springs between the follower-blocks; and links uniting the keys; the said links taking the strains in drawing and having elongated slots within which the front key moves in the act of buffing.
25. The combination in a draft and buffing gear, of a coupler and draw-bar with a slot; supports with elongated slots; keys within the slots and one of said keys passed through the slot in the draw-bar; a rear follower-block having a bearing against the rear key which key is movable from its normal position in one direction only; a front follower-block bearing against the end of the draw-bar; means for limiting the forward movement of the front follower-block in drawing; cushioning means between the follower-blocks; and links uniting the keys; said links taking the strains in drawing and being disconnected from the cushioning means and each having an elongated slot where it engages the rear key.
26. The combination with a draft and buffing gear having a draw-bar, slotted supports, front, middle and rear keys, and links which take the strains and advance the rear key and follower-block in drawing, of two follower-blocks; and two springs located side by side in a vertical plane between the follower-blocks; said follower-blocks being provided with means for engaging and holding the springs in place, and said rear key being movable only in drawing and said middle key movable only in buffing.
27. The combination in a draft and buffing gear, of a coupler and draw-bar; a front follower-block; a rear follower-block; a spring or springs between the blocks; slotted links; and keys; the rear key being movable from its normal position in a forward direction only; the key passed through the front follower-block being movable from its normal position in a rearward direction only; the two rear slots in each link being elongated; and the front follower-block and the key which supports it being movable together.
